ELECTRIC RANGE

Ralph M. La Zar, Skokie, and Ray C. Sandin, Northbrook, Ill., assignors to General Electric Company, a corporation of New York

Filed Aug. 13, 1959, Ser. No. 57,171

Term of patent 14 years

(Cl. D81—4)

Fig. 1 is a front perspective view of an electric range or the like showing our new design, the opposite side thereof being a mirror image of the side shown.

Fig. 2 is a fragmentary sectional view taken along the line 2—2 of Fig. 1.

Fig. 3 is a fragmentary sectional view of the rear panelled section taken along the lines 3—3 of Fig. 1.

The dominant features of the design reside in the portions shown in full lines.

We claim:

The ornamental design for an electric range substantially as shown and described.
